RAILWAY SWITCH LOCK CONTROL SYSTEM

Thomas Joseph Judge, Rochester, N. Y., assignor
to General Railway Signal Company, Rochester, N. Y.

Application February 5, 1943, Serial No. 474,775

10 Claims. (Cl. 246—161)

This invention relates to systems for safeguarding traffic on railroads, and more particularly to devices and circuit organizations for protecting hand-operated track switches located along the main track of a railroad.

Many railroads have track switches connecting with passing sidings, storage and industrial tracks, and the like, which are manually operated by a trainman from the normal or main track position to a reverse position as occasion may require for train movement into and from the main track. It will be readily appreciated that such hand operation of the track switch should not be performed for turn-out train movements if there is some other train on the main track which intends to pass over the switch in a main track position at speed, since a derailment or collision is likely to occur should a switch be thrown in front of a moving train. In order to provide for such circumstances, railroads usually have operating rules which require a trainman to receive special authority such as a written train order, permission obtained from a dispatcher over a telephone, or the like, before operating a switch to bring a train onto the main track; but since there is always opportunity for error in the execution of the orders received, it is desirable to provide what is commonly known as a switch lock with suitable automatic control which prevents hand operation of the switch except under safe conditions.

In one organization, a switch lock is provided so that a hand-operated track switch cannot be manually moved to a turn-out position unless the switch lock is released and this release does not take effect until after a predetermined time following the initial putting to stop of signals governing traffic over the main track by a preliminary manual act at the switch. Such an organization is commonly known as time locking, which permits an on-coming train to either be stopped by the signal on the main track having been put to stop, or to allow the train to come within sight or pass over such switch, it being assumed that the trainman will not throw the switch with a train within sighting distance or passing over such switch. This type of locking provides the essential protection for trains entering the main track, but it is obvious that a train leaving the main track would be unnecessarily delayed if the switch could not be operated until after a predetermined time. To obviate this unnecessary delay of a train leaving the main track, a short release track section is provided adjacent the switch to permit the release of the lock while

a train is on this track section. Such an arrangement is disclosed for example in the prior patent to S. N. Wight, Patent No. 1,476,866 dated December 11, 1923.

5 The present invention relates more particularly in the provision of a novel organization in connection with the provision of a release track section so as to make it unnecessary to provide control contacts in the wayside signal circuits at the track switch but still giving the usual protection of holding the signal at stop as soon as the initial manual act is performed at the out-lying track switch.

15 A further feature of the invention is that a release track section is included in the system of the present invention in a manner to obviate the necessity of providing a track battery individual to it.

20 A further feature of the invention is to so organize the release track section together with the releasing means for the switch lock that the organization may be employed with signalling of either the line circuit type or the coded track circuit type.

25 Various other characteristic features, attributes and advantages of the present invention will be in part apparent and in part pointed out as the description progresses.

30 In describing the invention in detail, reference will be made to the accompanying drawings, in which similar letter reference characters are used to designate similar parts throughout the various figures, in which like reference characters have been made generally distinctive by the use of distinctive preceding numerals, and in which:

35 Fig. 1 illustrates one embodiment of the present invention providing a switch lock organization associated with a line circuit type of signalling system; and

40 Fig. 2 illustrates another embodiment of the present invention providing a switch lock organization associated with a coded track circuit type of signalling system.

45 The accompanying drawings illustrate in a conventional and diagrammatic manner two specific embodiments of the present invention, the parts and circuits being shown in a manner to facilitate an understanding of the functions and operation of the invention, rather than to illustrate the detail structure and arrangement of parts preferably employed in practice. Thus, symbols are employed in the conventional manner for the various devices and sources of electric current instead of showing all of the wiring connections to the terminals of such sources.

The symbols (+) and (−) are therefore employed to indicate the connection to the positive and negative terminals respectively of suitable batteries or other sources of direct current, and the circuits with which these symbols are used always have current flowing in the same direction. The symbols (B+) and (B−) are used to indicate connections to the opposite terminals of a suitable battery or other direct current source which has a central or intermediate tap designated (C), and the circuits with which these symbols are used may have current flowing in one direction or the other dependent upon the particular (B+) or (B−) terminal used in combination with the intermediate tap (C). If alternating current is to be used instead of direct current, the polarity symbols employed are to be considered as instantaneous relative polarities.

The invention may be used in connection with any one of the various applications of hand-operated switches on both single and double track railroads having any suitable form of block signalling with or without supervisory manual control of the signals and the switch lock by a system of centralized traffic control. In one specific embodiment of the invention, it has been assumed for the sake of simplicity that the switch lock organization is applied to a typical outlying switch for the main track of a double track railroad equipped with a conventional automatic block signalling system using polarized line circuits; while in the other specific embodiment of the invention, it has been assumed that the switch lock is employed with a typical outlying track switch for the main track of a double track railroad equipped with conventional coded track circuits.

Referring to Fig. 1 of the drawings, a stretch of track is shown as divided into track sections AT, 1T, 2T and 3T. The track section 2T is in effect divided into three portions including a release track rail portion 2TB as well as a forward portion 2TA and a rearward portion 2TC. The release track rail portion 2TB is relatively short, for example, in the order of two or three-rail lengths with suitable insulated joints 7, 8 and 9 separating it from the other portions 2TA and 2TC of the track section 2T. It will be noted that this track section between the signals 2 and 3 is referred to as a whole by the reference character 2T, while its different portions are specifically referred to by the particular letter reference character A, B or C following the general term of 2T. This is for convenience in discussing the various characteristics of the release rail portion 2TB with respect to the rest of the track section 2T.

The movement of trains on the stretch of track shown is normally in an east-bound direction indicated by the arrow and legend. This east-bound traffic is governed by signals 1, 2 and 3, which may be of any suitable type, but have been shown as color light signals and are arranged to be controlled in accordance with established practice by polar neutral home relays H having suitable polarized line circuits. The relay 1H, for example, which governs the indications of the signal 1 in an obvious manner, is controlled over a polarized line circuit, readily traced on the drawings as including a front contact 5 of track relay 1TR, and a contact 6 of relay 2H which causes (B+) to be applied if the relay 2H is picked up but causes (B−) to be applied if the relay 2H is dropped away.

Thus, in the arrangement shown, if the track

section 1T is occupied by a train, the front contact 5 is opened and the home relay 1H is de-energized causing the signal 1 to indicate stop. But, if the train is in the track section 2T which causes the home relay 2H to be deenergized, then negative potential is applied to the home relay 1H so that the signal 1 is caused to indicate caution. Of course, under normal conditions with a train either in the track section 3T or further advanced, the relay 2H is picked up and positive potential (B+) is applied to the relay 1H so that the signal 1 normally indicates clear.

The stretch of track shown in Fig. 1 also includes a hand-operated track switch 2W which may be moved from one position to the other by any suitable hand-operated mechanism. Associated therewith is a suitable switch lock which has been diagrammatically illustrated for the purpose of disclosing the principles of the present invention, but this lock may be of any suitable type, such as disclosed for example in the Patent No. 1,710,668 granted to J. E. Stephenson, April 23, 1929. In this type of switch lock, a lock rod 10 is connected to the switch points and is held in a normal position by a lock plunger 11 locking the switch points in such normal position. The switch points cannot be moved to the reverse position in a direction indicated by the arrow associated with the lock rod 10 until the lock plunger 11 has been raised by a lock handle 2LH. This lock handle 2LH can be moved a limited amount opening certain contacts and closing others as will be later described, but is held in a locking position by the lock dog 12 which prevents the release of the lock rod 10 until the electric lock coil 2L is energized to move the locking dog 12 to non-engaging position. When the lock dog 12 is lifted by the energization of the lock coil 2L, then the lock handle 2LH may be moved in a counter-clockwise direction to raise the locking plunger 11 to disengage the hole in the lock rod 10 and permit hand-operation of the track switch to its reverse position. It will be noted that the lock handle 2LH cannot be returned to its normal position until the track switch 2W has been returned to its normal position for main line movement because with the lock rod 10 in a reverse position, there is no hole through which the lock plunger 11 may pass.

Also, associated with the switch 2W is a suitable switch box or circuit controller having contacts which are closed only when the switch is in a proper normal or reverse position and this switch box is shown as having contacts 14 closed in the normal position only. For simplicity in the disclosure, these contacts are indicated as operated by the lock rod 10, but usually a separate rod is employed to connect such contacts with the switch points.

Other elements of the switch lock include door contacts 15 which assume one position when the door (not shown) for the switch lock casing is closed, but assume another position when the door of the casing is open, it being understood that this door must be open in order to gain access to the lock handle 2LH. The structure of the switch lock casing may also be such as to prevent the closure of the door to operate contacts 15 to their normally closed positions unless the lock handle 2LH is in its normal position.

Also associated with the electric switch lock is a time element device 2DT which may be of any suitable type. This time element device is slow-

acting, and has a checking contact 17 which is opened as soon as the device is set into operation and is not again closed in its back point position as shown until the device 2TD has been fully restored to normal. A timing contact 18 is provided on this timing device 2TD which is not closed until after a predetermined interval of time has been measured, but is immediately opened as soon as the timing device 2TD is deenergized. This timing device 2TD may be of any suitable type, such as shown for example in the Patent No. 2,192,335 granted to O. S. Field, April 30, 1940, or it may be a thermal relay and an associated repeating relay, or any other suitable organization for measuring a relatively long time interval such as for example four to six minutes.

Under normal conditions, the track battery 20 supplies energy through a circuit including the upper rail of track section 2TC, over the jumper cable 21, to the lower rail of track section 2TA, through the track relay 2TR to the upper rail of track section 2TA, through suitable track connections including back contact 22 of relay 2WLT, front contact 23 of relay 2WLP, to the release rail 2TB, and over suitable track connections including front contact 24 of relay 2WLP, to the lower rail of track section 2TC, to the negative side of the track battery 20. Thus, the track relay 2TR is energized closing front contact 30 so that relay 2H is energized and signal 2 for the main track indicates clear.

The switch 2W is of course assumed to be in a normal position and locked with the door of the switch lock casing closed so that energy is supplied from (+), through a circuit including door contact 15 in a right-hand position, windings of a relay 2WLP, back checking contact 17 of timing device 2TD, back contact 25 of lock magnet 2L, lock contact 26 in a normal position N, switch box contact 14 in a normal position to (-).

This energization of the switch lock repeating relay 2WLP maintains its front contacts 23 and 24 closed so as to complete the track circuit 2T, as above pointed out.

In connection with the operation of hand-operated track switches, particularly in territory where there is supervisory manual control over the signals and power-operated track switches by a centralized traffic control system, it may be desirable to provide manual supervisory control over the switch lock in order to give the dispatcher or operator control over the release of the track switch. This is provided particularly to prevent the switch from being hand-operated to allow a train to come onto the main track when such movement is contrary to the wishes of the dispatcher and might otherwise occur due to the careless action of a train crew or perhaps due to a misunderstanding of the dispatcher's instructions received over a telephone. Although, such manual supervision of the outlying switch lock may be provided if desired, this has not been shown in connection with the present disclosure for the sake of simplicity, but may be readily applied to the organization disclosed if this is desired.

Assuming that a trainman has received orders over the telephone that he may operate the track switch 2W to a reverse position and allow his train to proceed over the main track, it is assumed that the trainman opens the door of the switch lock casing and thus permits the contact 15 to be operated to a left-hand position. This immediately deenergizes the relay 2WLP

10 opening front contacts 23 and 24 causing the track relay 2TR to be immediately deenergized opening its front contact 30 and thereby causing the signal 2 to be placed at stop and the signal 1 to indicate caution. As soon as the back contact 31 of relay 2WLP is closed, it is apparent that a circuit is closed from (+), and including door contact 15 in a left-hand position, back contact 31 of relay 2WLP, windings of timing device 2TD, to (-). This energization of the timing device 2TD immediately opens the checking back contact 17 and begins to measure off a predetermined time after which front contact 18 will be closed.

15 The trainman will then move the lock handle 2LH apart of its possible movement away from its normal position which opens contact 26 in the normal position thus further insuring that the relay 2WLP is deenergized, and closes contact 32 in the position commonly known as the B position. This contact 32 is also completed with the lever 2LH in any other position up to the reverse position. Such a contact is commonly termed an RB contact. Thus, after a predetermined time has been measured by the slow-acting timing device 2TD, front contact 18 is closed and a circuit is closed including contact 32 in the B position to energize the lock magnet 2L. The energization of this lock magnet 2L raises the locking dog 12 to release the lock handle 2LH, and at the same time opens back contact 25 also included in the circuit for the relay 2WLP. With the dog 12 in a raised position, the lock handle 2LH may be moved to its unlocking position so that the lock plunger 11 will release the switch 2W and permit it to be manually operated to its reverse position.

20 It will thus be seen that a train standing on the turn-out track may receive instructions to enter the main track, and when the door of the switch lock box is opened, the signals are placed at stop by interrupting the track circuit controlling the passage of traffic over the track switch 2W, but the switch is not released for movement to its reverse position until after such signals have been held at stop for a predetermined period of time.

25 When the train has passed over the switch 2W onto the main track, the trainman then operates the switch 2W to its normal position replacing the lock handle 2LH which deenergizes the lock magnet 2L and also closes contact 26 in a normal position. Thus, as soon as he closes the door of the switch lock casing, contact 15 is moved to a right-hand position completing a circuit for the relay 2WLP as soon as the slow-acting timing device assumes its restored normal position closing checking contact 17.

30 Considering the above description with respect to Fig. 1, it will be seen that the initial opening of the door of the switch lock, deenergizes the relay 2WLP, which opens the circuit for the track relay 2TR at front contacts 23 and 24 so that the track relay 2TR is deenergized opening front contact 30 to deenergize the home relay 2H. This causes the signal 2 to display a stop indication and to so control signal 1 in the rear thereof so that it displays a caution indication. The entrance of the train into the track section 2T of course maintains signal 2 at stop even though the track switch 2W is restored to its normal position in the rear of the train.

35 It is assumed that the train leaving the turn-out track will proceed in an east-bound direction corresponding to the normal direction of traffic.

after the switch 2W has been restored to its normal position. However, a train might proceed in the west-bound direction against the normal direction of traffic either under special orders from the dispatcher or suitable reversed signalling might be employed although the present disclosure does not show such signalling for both directions of traffic.

With the normal direction of traffic for east-bound train movements, it will often happen that a train in approach to signal 2 will desire to enter the turn-out track. The train in passing the signal 2 of course deenergizes the track relay 2TR by shunting the track rails of the track section portion 2TA, and this deenergized condition of the track relay 2TR is maintained throughout the time that the east-bound train is in any portion of the track section 2T and until such train either passes beyond the signal 3 or over the switch 2W onto the turn-out track.

Assuming that the train desires to enter the turn-out track, it proceeds onto the release rails 2TB which still maintains the shunt on the track relay 2TR in an obvious manner. The train stops and sends a trainman to the switch 2W who opens the door to the switch lock casing which moves contact 15 from its right-hand position to its left-hand position. This deenergizes the relay 2WLP and sets the slow-acting timing device 2TD into operation. However, the trainman immediately begins to operate the handle 2LH because with the train on this release track rails 2TB it is unnecessary for the predetermined time of the slow-acting timing device 2TD to elapse before the switch lock is released. This is because the presence of the train completes a circuit from the lower rail of track section portion 2TC through back contact 24 of relay 2WLP, relay 2WLT, back contact 23 of relay 2WLP, release track section 2TB through the axles of the train to the upper rail of the track section 2TC. This circuit causes the energization of the relay 2WLT closing front contact 35. Thus, as soon as the trainman moves the handle 2LH to the B position, a circuit is completed through contact 32 for energizing the locking magnet 2L and permitting the continued operation of the handle 2LH to release the switch 2W for manual operation. The energization of the lock magnet 2L opens back contact 25, while operation of lever 2LH from a normal position opens normal contact 26, and the operation of the switch 2W to a reverse position opens switch box contact 14, all in a manner previously described, so that the relay 2WLP is maintained deenergized until the train has passed over the turnout track and the trainman has restored the switch 2W and lock mechanism to its normal condition in the rear of such train.

In this way it is seen that an east-bound train may pass onto the turn-out track without waiting for the predetermined time to elapse as measured by the slow-acting timing device 2TD, which is effected through the release track rails 2TB. It is noted that the energization of the relay 2WLT is accomplished by what may be termed a series relay connection to the track which is supplied with energy from the track battery 20. The present organization is protected against the undesired and accidental breaking down of the insulated joints for the release track rails 2TB. For example, if the insulating joint 8 should break down, then the shunt 21 connects the lower rail with the upper rail so that the track relay 2TR is deenergized and the signal 2 is placed at stop. Similarly, if the insulating joint 9 should acci-

dentially break down, then a circuit is closed from the upper rail through back contact 22 of relay 2WLP, front contact 23 of relay 2WLP, to the lower rail, thus shunting the track relay 2TR so that it drops away under such circumstances and causes the signal 2 to indicate stop. Thus, any erroneous break-down condition of the insulated joints 8 and 9 is self-betraying through the control of the signal 2. The break-down of the insulating joint 7 during the absence of traffic produces no unsafe conditions with respect to the signalling system, but is not self-betraying until the use of the release track section is desired. For example, it is seen that the break-down of the insulating joint 7 causes a shunt across the track relay 2WLT so that the switch lock will not be released until after a predetermined time even though a train is standing on the release track rails 2TB.

In this way, release track section control of a switch lock is provided without the use of an additional track battery and in a manner which properly maintains the signals at stop while the switch is unlocked and protects against accidental breaking down of the insulated joints associated with the release track section.

Operation of Fig. 2.—The principles of the invention have been disclosed in Fig. 2 in connection with the use of coded track circuits for the signalling system. The same type of track layout is shown in Fig. 2 as is shown in Fig. 1, but the track sections have been designated as track sections 4T, 5T, 6T, and 7T, the track section 6T being divided up into a forward portion 6TA, a release track 6TB, and a rear portion 6TC. Signals 5, 6 and 7 are shown for governing traffic over their respective track sections. These signals are shown as controlled by the usual coded track circuit apparatus.

More specifically, a code following track relay 6TR is associated with the signal 6, and operates at the particular code rate received over the track section. The track relay 6TR acts through suitable decoding apparatus to cause the relay 6H to be maintained energized whenever any code is being received, but causes the energization of the relay 6D only when a particular code rate is being received. For example, the code rates 75 and 180 impulses per minute may be employed, the 75 code rate being for a caution control and the 180 code rate being for the clear code period. The reception of the 75 code by the track relay 6TR will cause only relay 6H to be picked up, while the reception of the 180 code by the track relay 6TR will cause both relays 6H and 6D to be picked up. Similar operation occurs in connection with the decoding apparatus at all of the signal locations.

Associated with each signal is a code transmitting relay CP which is controlled in accordance with the condition of energization of the associated home relay so as to impress a clear or caution code in the rear of that signal depending upon traffic conditions in advance. For example, the code transmitting relay 6CP is controlled in accordance with a 180 code oscillator 180CT through front contact 50 of relay 7H under normal conditions. But if a train is in the block in advance of the signal 7, then the relay 7H is deenergized closing back contact 50 so that the code transmitter 6CP is controlled in accordance with the operation of a 75 code oscillator 75CT. These code transmitters or oscillators CP may be of any suitable type, such as motor driven contactors, or of the spring balance type such as

shown in the prior application of O. S. Field, Ser. No. 369,862, filed December 12, 1940, it being sufficient for the purpose of the present invention to know that these contacts are operated at some predetermined code rate such as indicated by their preceding numerals.

The operation of the code transmitting relay 6CP intermittently closes front contact 51 to intermittently connect the battery 52 across the track rails of its associated section 6T. This supplies energy to the code following track relay 6TR over a track circuit including front contact 53 of relay 6WLP, the release track 6TB, front contact 54 of relay 6WLP, polar contact 55 of relay 6WLT in a left-hand position. Thus, the code following track relay 6TR receives code as transmitted from the exit end of its associated track section 6T. Under normal conditions, this code is of course a clear code of the 180 code rate so that both the relays 6H and 6D are picked up completing a circuit for the green lamp of signal 6 through front contacts 56 of relay 6H and front contact 57 of relay 6D. On the other hand, if the code is of the caution 75 code rate, the relay 6D would be deenergized closing back contact 57 to energize the yellow lamp of signal 6. If both relays 6D and 6H are deenergized, then it is obvious that the back contact 56 of relay 6H energizes the red lamp of signal 6. In a similar manner, each signal is controlled by coded track circuits in accordance with traffic conditions in advance, it being understood of course that a release track, such as 6TB, is included only in those sections where a switch lock is employed.

The switch lock apparatus for Fig. 2 is exactly the same as shown in Fig. 1 and is controlled in exactly the same manner except that the release track section relay 6WLT is of the polar magnetic stick type. In other words, this relay is provided with a polarized structure so as to operate its contacts to one position or the other depending upon the polarity with which it is energized, but its contacts remain in their last actuated positions until energized with the opposite polarity. Thus, the description with regard to the operation of the switch lock as given in connection with Fig. 1 will apply to the operation with respect to Fig. 2 except as to the operation surrounding the use of the release track sections 6TB involving the control of this relay 6WLT.

More specifically, it is believed unnecessary to point out in detail how the track switch 6W may be released for a train on the turn-out track which is to enter the main track because the slow-acting timing device 6TD operates after a predetermined time under such circumstances to close to front contact 60 and energize the lock magnet 6L to release the lock handle 6LH in the same manner pointed out in detail in connection with Fig. 1.

However, a train standing on the release section 6TB desiring to enter the turn-out track causes operation of the relay 6WLT to a right-hand position by reason of the current flow through the lower winding of this relay 6WLT when the trainman opens the door of the switch lock casing and contact 58 closes in a left-hand position. More specifically, this circuit for relay 6WLT includes from the positive side of battery 52, lower rail of 6TC, back contact 53 of relay 6WLP, lower winding of relay 6WLT, back contact 54 of relay 6WLP, release track section 6TB, axles of the train, upper rail of the track section 6TC, to negative side of battery 52. Although only pulses of code current pass through this circuit,

they cause the polar contacts of the relay 6WLT to operate to right-hand positions so that contact 61 completes an obvious circuit for the energization of the lock magnet 6L as soon as the trainman operates the lever 6LH to its B position. The energization of the lock magnet 6L releases the handle 6LH so that the operator can move it to a releasing position. The trainman then manually operates the switch 6W to its reverse position for the passage of the train onto the turn-out track. It is to be understood that the operation of the switch box contacts and other contacts associated with the switch lock have the same functions as described in connection with Fig. 1.

Assuming that the train passes over the track switch onto the turn-out track and that the trainman restores the train switch 6W to its normal position as well as restoring the switch lock to its proper normal condition, then as soon as the relay 6WLP picks up, energy is supplied from the positive side of battery 52, over the lower rail of the track section 6TC, through front contact 53 of relay 6WLP, release track section 6TB, front contact 54 of relay 6WLP, polar contact 55 in a right-hand position, upper winding of relay 6WLT, through the upper rail of the track section 6TC, to the negative terminal of battery 52. The energy applied to this circuit is in the form of impulses of coded current, as applied by the code transmitting relay 6CP. The first impulse will cause the contacts of the relay 6WLT to be operated to left-hand positions. In this connection, it is to be understood that if the circuit should be closed for this relay near the end of an impulse, such impulse might not operate the polar contacts of the relay 6WLT, but the first impulse which is sufficiently complete to supply the proper amount of energy for such relay, will operate the polar contacts of this relay to their opposite positions. Also, a polarized relay of the two-position type is so constructed that its contacts will not remain in intermediate positions, so that if an impulse is applied through its own contacts 55 in sufficient amount of energy to operate the relay, its contacts move to their opposite positions, although its energizing circuit may in the meantime be interrupted.

As soon as the contact 55 is operated to the left-hand position, the normal condition of the track circuits is restored so that the code following track relay 6TR will receive the code as applied to the track section 6T by the code transmitting contact 51 of relay 6CP. The signal 6 is thus caused to indicate clear, assuming that there is no train in the track section 6T in advance of the signal 1.

It is noted that the same protection is provided in this form of the invention in the event of the break-down of insulated joints as described in connection with Fig. 1. More specifically, if the insulated joint 62 breaks down, this does not affect the signal 6 under normal conditions, but if a train enters the track section 6TA and approaches the switch 6W on the release rails 6TB, the switch lock cannot be released by the relay 6WLT, because with the joint 62 broken down there is no potential drop for the energization of the lower winding of the relay 6WLT. In such a case, the switch lock may be released only after the elapse of the predetermined time measured by the time element device 6TD. It is assured that the contact 61 is normally in a left-hand position because if the contacts of the relay 6WLT fail to assume their left-hand positions

as effected through the restoration circuit including front contact 54 of relay 6WLP, and polar contact 55 of relay 6WLT, the signal 6 would be held at stop inasmuch as the normal completion of the track circuit through the section 6TA requires the polar contact 55 to be in a left-hand position.

If the insulated joint 63 breaks down, then it is obvious that the release rail section 6TB is connected to the upper rails of the track section 6TC and energy is shunted away from the code following track relay 6TR. This causes the signal 6 to remain at stop and thus the failure of insulated joint 63 becomes self-betraying.

The breaking down of the insulated joint 64 also completes a shunt for the track section 6TB through front contact 54 of relay 6WLP, polar contact 55 of relay 6WLT in a left-hand position past the broken-down insulated joint 64 to the upper rails of the track section 6TA. This shunt of energy away from the code following track relay 6TR holds the signal 6 at stop so that the broken-down condition of the insulated joint 64 is also self-betraying. It is thus believed, that the switch lock of the present invention is provided with release circuits organized on the closed circuit principle.

In this way, a release track section and its associated control circuits for governing a switch lock have been provided in a manner which is equally applicable to coded track circuits or conventional normally energized track circuits.

While certain features of the invention are applicable to and usable with any type of signaling system, whether obtained by line wire control or some form of coded track circuit, the specific embodiments of the invention illustrated shows the invention applied to one direction signalling, but the invention should be considered from its broadest aspects and not limited for use with such a specific form of signalling.

Having described a system of switch lock control in two different specific embodiments of the present invention, it is desired to be understood that these forms are selected to facilitate in the disclosure of the invention rather than to limit the number of forms that it may assume; and it is to be understood that various modifications, adaptations and alterations may be applied to these specific forms shown to meet the requirements of practice without in any manner departing from the scope of the present invention except as limited by the appended claims.

What I claim is:

1. In a system for protecting hand-operated track switches on railroads, a manually operable track switch, manually operable locking means for the track switch, an electric lock acting when deenergized to prevent manual release of said locking means, a time element device operable when manually initiated for energizing said electric lock only after a predetermined time, a normally closed track circuit associated with said track switch and including a release rail normally connected in series therewith, a signal for governing traffic over said track switch and controlled to indicate clear only when said track circuit is energized, a track relay associated with said release rail, means for opening said track circuit to cause said signal to indicate stop and for connecting said track relay in series with said release rail and a portion of said track circuit to thereby effect the energization of the track relay when the release rail of the track

circuit is occupied by a train, and circuit means for at times effecting the energization of said electric lock when said track relay is energized.

2. In a system for protecting hand-operated track switches on railroads, a hand-operated track switch, locking means normally acting to prevent manual operation of the track switch, a normally energized track circuit associated with said track switch and including a release rail section normally connected in series with such track circuit, a signal governing traffic over said switch in accordance with the energized condition of said track circuit, means for at times opening said track circuit to cause said signal to indicate stop and for connecting a series track relay in series with said release rail section and the remaining portion of said track circuit to thereby effect the energization of said series track relay when the release rail section is occupied by a train, and circuit means controlled by said series track relay for at times causing the release of said locking means.

3. In a system for protecting hand-operated track switches on railroads, a manually operable track switch, an electric lock normally deenergized and acting to prevent the manual operation of said track switch while deenergized, a normally closed track circuit section associated with said track switch and including a release rail section normally connected in series with said track circuit, a track relay located at the entrance end of said track circuit and normally energized over said track circuit from a source of energy located at the exit end of said track circuit, a signal governing traffic into said track circuit and over said switch, said signal indicating clear only providing said track relay is energized, a series track relay associated with said release rail section means for at times opening said track circuit to deenergize said track relay and at the same time connect said series track relay in series with said release rail and the portion of the track circuit adjacent said switch to thereby effect the energization of said series track relay from said source of energy if the release rail section of the track circuit is occupied by a train, and circuit means for energizing said electric lock to release said track switch only providing said series track relay is energized, whereby said track switch cannot be released by said series relay becoming energized unless the signal governing traffic thereover is first caused to indicate stop.

4. In a system for protecting hand-operated track switches on railroads, a stretch of railway track including a hand-operated track switch and having a signal at the entrance end thereof for governing traffic over the stretch including such track switch, a locking device normally preventing hand operation of the track switch, a track relay adjacent said signal and effective to govern indications thereof in a manner to allow said signal to indicate clear only providing such track relay is energized, a source of energy at the exit end of the stretch connected across the rails thereof, insulated joints included in one rail of the stretch for separating a release rail section from a forward portion of the stretch and a leaving portion of the stretch, an insulated joint in the other rail of the stretch adjacent the release track section and effective to divide the forward portion of the stretch from the leaving portion of the stretch, circuit means normally effective to connect said release rail section and said forward and leaving

portions of the stretch in a manner to provide a normally energized track circuit including said track relay and said source with a cross-connection between the two tracks at the release rail insulated joints providing that the break-down of the insulated joint in either track effects a shunting of the track relay, a series track relay associated with said locking device adjacent said switch, and circuit means at times effective to open said track circuit at said release track section and to connect said series track relay in series with said release track section and said leaving portion of the stretch to thereby effect the deenergization of said track relay adjacent said signal and permit the energization of said series track relay from said source of energy when a train occupies said release track section, and circuit means governed by said series track relay for at times releasing said locking device associated with said track switch.

5. In a system for protecting hand-operated track switches on railroads in coded track circuit territory, a manually operable track switch, a locking means normally effective to prevent manual operation of the track switch, circuit means effective to divide a coded track circuit into a forward portion and a leaving portion with an intervening release track section, but normally connecting all three portions of the coded track circuit in series, said means at times acting to open said track circuit at said release track section to prevent the transmission of code impulses through said forward section and at the same time render a switch lock track relay responsive to the coding impulses in the leaving portion of the track circuit only when a train is occupying said release track section, and manually controlled circuit means for releasing said locking means when said switch lock track relay is energized.

6. In a system for protecting hand-operated track switches on railroads, a manually operable track switch, a manually operable switch locking means for the track switch, an electric lock acting when deenergized to prevent manual release of said switch locking means, a coded track circuit associated with said track switch and having code transmitting means at the end adjacent said track switch, a code following track relay at the other end, and a release rail at an intermediate portion of said track circuit suitably insulated from the rails of the entering and leaving portions of the track circuit, a code responsive means associated with said release rail, circuit means normally effective to connect said release rail in series with said entering and leaving portions of said track circuit but acting when actuated to disconnect said release rail from that entering portion of said track circuit including said code following track relay and to connect said code responsive means in series with said release rail and that leaving portion of said track circuit including said code transmitting means, to thereby provide that said code responsive means associated with said release rail will effectively receive code from said code transmitting means only when a train occupies that portion of the track circuit including said release rail, and circuit means governed by said code responsive means associated with said release rail when it is effectively receiving code for at times effecting the energization of said electric lock.

7. In a system for protecting hand-operated track switches on railroads, a manually operable track switch, a manually operable switch locking

means for the track switch, an electric lock normally acting while deenergized to prevent manual release of said locking means, a track circuit associated with said track switch and including a battery at the end adjacent said track switch, a track relay at the other end and a release rail at an intermediate portion of the track circuit in a facing point position with respect to said switch and insulated from the other rails of the track circuit by insulated joints, a series track relay associated with said release rail circuit means normally effective to connect said release rail in series in said track circuit but acting at other times to disconnect said release rail from said track circuit at its end nearest said track relay and also to connect said series track relay in series with said release rail and said track circuit at its other end adjacent the track switch, to thereby provide for the effective energization of said series track relay when the portion of the track circuit including the release rail is occupied by a train, and circuit means including a front contact of said series track relay for at times energizing said electric lock to allow manual release of said switch locking means.

8. In a system for protecting hand-operated track switches on railroads, a track section including a track switch at one end and a signal at the other end, the two rails of said section forming a track circuit having a track battery at the end adjacent the track switch and a track relay at the end adjacent said signal, and a release portion at an intermediate point with its rails insulated from the rails of the rest of the track circuit, a series track relay associated with said release portion of said track circuit, circuit means normally effective to connect said release portion in series with said track circuit, said connection at its end nearest said signal acting to connect the two rails of said release portion to the respective opposite rails of said track circuit nearest said signal, but acting when actuated to disconnect said release portion from said track circuit adjacent said signal and at the same time connect said series track relay in series with said release portion and said track circuit adjacent said track switch to thereby effect the energization of said series track relay when the release portion of the track circuit is occupied by a train, circuit means for governing said signal in accordance with the energized condition of said track relay adjacent said signal, an electric lock acting when deenergized to prevent operation of said track switch, and circuit means for effecting the energization of said electric lock when said series track relay is energized, whereby the inclusion of said series track relay in series with said release portion and said track circuit adjacent the switch acts to prevent the energization of said track relay at said signal for holding said signal at stop.

9. In a system for protecting hand-operated track switches on railroads, a manually operable track switch included in a stretch of track, locking means acting while deenergized to prevent manual operation of the track switch, means for dividing said stretch of track into a track circuit having entering and leaving portions separated by a release rail section in a facing point position with respect to said switch, normally closed circuit connections for connecting said release rail section in series with the entering and leaving portions of said track circuit, code transmitting means at the exit end of the track circuit for applying distinctive code impulses of

a particular polarity to said track circuit, code receiving means at the entrance of said track circuit responsive to the different codes received for governing the entrance of traffic into said stretch, a double wound series track relay of the two position polarized magnetic stick type associated with said release rail section and normally assuming a particular polar position, control means for at times opening said normal circuit connections and connecting one winding of said series track relay in series with said release rail section to thereby prevent the energization of said code receiving means and to permit the energization of said series track relay to an opposite polar position by said code impulses of said particular polarity when the release rail section is occupied by a train, circuit means governed by said series track relay when energized to said opposite polar position for releasing said locking means, and restoration circuit means temporarily effective upon the restoration of said control means to effect the energization of another winding of said series track relay by said code impulses of said particular polarity to cause its operation to said normal polar position, the contacts of said series track relay in their normal positions being included in said normally closed circuit connections for connecting said release rail section in series in said track circuit, whereby said track circuit is restored to normal conditions for operation of said

code receiving means only providing the polar contacts of said series track relay are in positions which cannot effect the release of said locking means.

- 5 10. In a switch lock controlling system, a manually operable track switch, a locking device acting while deenergized to prevent operation of said track switch, a signal for governing traffic over said switch in a facing point direction, a track circuit associated with said switch for controlling the indications of said signal in accordance with the energization of said track circuit from a source located at the exit end of the track circuit, a switch lock track relay associated with said locking device, circuit means effective to divide said track circuit into a forward portion and a leaving portion with an intervening release portion but normally connecting all three portions of the track circuit in series, said circuit means being manually controllable to open said track circuit at said release portion to prevent the flow of energy from said source in said forward portion and at the same time render said switch lock track relay responsive to energy received over said leaving portion from said source only when a train is occupying said release portion, and circuit means for at times energizing said locking device while said switch lock track relay is energized.
